UNITED STATES PATENT OFFICE

WILLIAM WENDELL MACHEMER, OF BROOKLYN, NEW YORK, ASSIGNOR OF ONE-HALF
TO JOHN EICHENAUER, OF BROOKLYN, NEW YORK

COLLAPSIBLE CASE

Application filed August 29, 1928. Serial No. 302,797.

This invention relates to collapsible cases and while the apparatus may have many uses as a case for storing and shipping its primary use is that of a piece of hand baggage simulating what is commonly known in the trade as a suit case.

An object of the invention is to provide a case of this character made up of a plurality of sections which enable the case to be enlarged or contracted in accordance with the quantity of material to be carried and which will operate with equal facility in any position of adjustment.

A further object is to provide a neat and attractive telescoping suit case with an improved arrangement of handle and mount therefor whereby the position of the handle may be located in accordance with the disposition of the weight within the case.

With these and other objects in view, the invention consists in certain novel features of construction and combinations and arrangements of parts which will be more fully hereinafter described and pointed out in the claims.

In the accompanying drawings—

Figure 1 is a perspective view of my improved case showing the same in full lines in contracted position and illustrating by dot and dash lines the case when completely extended;

Figure 2 is a view in longitudinal section on the line 2—2 of Figure 1;

Figure 3 is a view in transverse section on the line 3—3 of Figure 2;

Figure 4 is an enlarged fragmentary view on the line 4—4 of Figure 2.

My improved case comprises two sections A and B, the latter slightly smaller in all transverse dimensions so as to fit and telescope within the section A. These sections A and B may be of metal, leather, cane or any other suitable material, and may be ornamented and decorated in any way to suit the trade. In the drawings I have illustrated the sections of metal although they may be of leather or other sheet material but I do not wish to be limited in this respect.

The sections A and B are of general rectangular shape having a greater longitudinal

dimension than any transverse dimension, so that the case has the appearance of what is known in the trade as a suit case although of course the exact shape of the case may be varied without departing from the invention.

The sections A and B at their inner ends are open and in communication with each other. The section A at its sides is formed with guides 1, 1 which may constitute inwardly bent portions of the edges of the sides to receive therein flanges 2 at the upper edges of the sides of section B so as to hold the sections A and B in proper relation to each other but permit sliding movement of the sections relative to each other to extend or contract the case.

This movement of the sections relative to each other is limited by a bar or strip 3 secured to the bottom of section B and having in its under face a longitudinal groove 4 which registers with a slot 5 in the bottom of section B but is of appreciably greater width than the slot, as clearly shown in Figure 4 of the drawings.

A stop piece 6, shaped somewhat after the manner of a staple, is projected through an opening in the section A and has its headed portion in the groove 4 of bar 3, and the engagement of this stop piece 6 with the groove 4 of bar 3 functions to limit the telescoping action of the case.

I do not wish to be limited to the particular form of stop piece indicated but desire to cover the idea of a piece fixed to one section and movable in the grooved bar of the other section to limit the telescoping action of the case.

A telescoping cover C is adapted to close the case, and this telescoping cover comprises two sections 7 and 8, the edges of one section being bent forming guides 9 for flanges 10 on the other section so as to hold the sections in proper relation under all conditions.

The section 7 carrying the guides 9 is connected by hinges 11 with the section A, and as both of these sections have flanged edges 12 overlapping the edges of the sections of the case a longitudinal movement of one relative to the other will cause the cover to tele-

scope in the same manner as the body portions of the sections telescope.

Any suitable form of catch or lock may be employed to secure the cover in closed position, and I have indicated a standard type of catch 13.

On the section A I locate a rod 14 secured in suitable brackets 15 and provide a series of notches 17 in the under face of the rod. 10 18 represents a handle having loops 19 at its ends receiving the rod 14, and this handle may be moved longitudinally of the rod 14 and the loops 19 engage in any of the notches 17 in accordance with the desired position of 15 the handle with regard to the disposition of weight in the case.

To hold the sections of the case against movement relative to each other, I provide a spring bolt 20 carried by a bracket 21 fixed to the inner face of section B, and this spring bolt is adapted to pass through openings 22 in the wall of section B and engage in sockets 23 in the wall of section A.

The spring bolt 21 is of such length that 25 when the cover C is in closed position it will hold this bolt projected through an opening 22 and into a socket 23 so that in order to adjust the case it is necessary to first raise the cover and release the spring-pressed bolt.

The operation is as follows:

Assuming the case to be contracted and it is desired to telescope the same, the cover C is lifted and section B is drawn out the desired length or to such position as to allow the spring bolt 20 to properly function. When the cover C is closed the spring bolt 20 will be forced into its holding position, as shown in Figures 2 and 3, and there can be no accidental movement of the case.

While I have illustrated what I believe to be a preferred embodiment of my invention, it is obvious various changes and alterations might be made in the general form of the 45 parts described without departing from the invention and hence I do not limit myself to the precise details set forth but consider myself at liberty to make such changes and alterations as fairly fall within the spirit and 50 scope of the appended claims.

I claim:

1. A telescoping case, comprising a plurality of sections, a rod fixed to one section and having notches in its under face, and a 65 handle adjustable on the rod and adapted to engage in any of said notches whereby the handle may be positioned as desired longitudinally of the case, said handle having loops at its ends receiving the rod and adapted to engage in the notches of the rod.

2. A telescoping case, comprising two sections, a cover on the sections, means on the sections limiting the longitudinal movement of one section relative to the other, and a 80 spring bolt carried by one section and held

in operative engagement with the other section by the cover when the latter is in closed position whereby the sections are held against independent movement when the cover is closed.

3. A telescoping case, comprising two sections movable longitudinally relative to each other, a cover hingedly connected to the case and comprising two sections movable longitudinally relative to each other, and means operated by the cover for securing the sections of the body against movement when the cover is closed and permitting longitudinal movement of the sections of the body when the cover is opened.
